UNITED STATES PATENT OFFICE.

ALBERT H. LUMM, OF TOLEDO, OHIO.

VENTILATOR.

1,254,517.

Specification of Letters Patent. Patented Jan. 22, 1918.

Application filed August 20, 1917. Serial No. 187,218.

To all whom it may concern:

Be it known that I, ALBERT H. LUMM, a citizen of the United States, residing at Toledo, in the county of Lucas and State of Ohio, have invented certain new and useful Improvements in Ventilators; and I do declare the following to be a full, clear, and exact description of the invention, such as will enable others skilled in the art to which 10 it appertains to make and use the same.

This invention relates to certain new and useful improvements in ventilators which are designed to be used in connection with chimneys, vent pipes and the like.

15 The primary object of the invention is to provide a ventilator which is normally maintained in closed position, but which opens automatically when there is a draft through the chimney or vent pipe and which further is closed on the windward side when 20 the wind blows to prevent a back draft down the chimney or vent pipe.

Another object of the invention is to provide a device of this character which will 25 be extremely simple, strong, durable and inexpensive in construction, efficient and reliable in operation and well adapted to the purpose for which it is designed.

With these and numerous other objects in 30 view, the invention consists of certain novel features of construction, and the combination and arrangement of parts as will be hereinafter fully described and claimed.

In the accompanying drawings forming a 35 part of the application and in which similar reference characters are used to designate like parts throughout several views:

Figure 1 is a side elevation of a ventilator constructed in accordance with this invention;

Fig. 2 is a vertical sectional view of the 40 ventilator, the said view being taken on the plane indicated by the line 2-2 of Fig. 1;

Fig. 3 is a horizontal sectional view of the 45 ventilator taken on the plane indicated by the line 3-3 of Fig. 2 and

Fig. 4, is a perspective view partly broken away and in section of a portion of the ventilator, the crown or dome thereof being removed.

50 Referring more particularly to the drawings, the numeral 1 designates a housing or air chamber which is here shown of hexagonal shape, but which may be provided with any number of sides. The housing 1

is constructed from a rectangular piece of sheet metal, said piece of sheet metal being bent in a number of places to form the sides 2 of the housing. Arranged in each of the sides 2 of the housing is a window or opening 3, the vertical side edges of which are bent laterally inwardly to form casings 4 for the windows. If desired the inner edges of the casings 4 may be bent laterally toward each other as shown in 5.

The reference numeral 6 designates a strip of angle metal which is bent into hexagonal shape to conform to the shape of the housing and which has the upper edge of its vertically disposed portion crimped over 60 and around the upper edge of said housing as clearly shown at 7 in the drawings. Soldered to this strip of angle metal 6 is a cone shaped crown or dome 8. This closes the top of the housing and aids in preventing 70 rain, snow, and the like from gaining entrance into the same. The inner edge of the horizontally disposed portion of the angle metal 6 is struck downwardly as shown at 9. A similar piece of angle metal 10 is arranged at the lower edge of the housing 1.

The reference numeral 11 designates a flue tube or draft pipe which is adapted to be 75 fixed on the chimney or vent pipe in any suitable manner, and which is secured to the lower end of the housing 1 by means of a plurality of radially disposed arms 12, one of the ends of said arms being secured to the tube 11 while their other arms are secured to the housing. The tube 11 is of less diameter than the distance between the opposite sides of the housing 1, and hence a space between the sides of the housing and the wall of the tube is provided. It is to be understood that air may pass through this space 80 into the housing and cause a draft up the tube 11 and through the chimney or vent pipe.

Soldered in the corners formed by the adjacent sides 2 of the housing 1 and disposed on the interior of the housing and between the adjacent window casings 4 are forms 13, two of the sides of which are disposed parallel to and slightly spaced from the window casings 4 for a purpose to be 100 105 hereinafter described.

Extending horizontally across each of the windows 3 and having their ends projecting through the window casings 4 is a series of vertically disposed rods or pins 14. The 110

opposite ends of the rods or pins 14 abut against the above mentioned forms 13 and prevent said rods or pins from longitudinal shifting.

5 These rods or pins 14 form the pivots or hinges for a series of shutters 15, said shutters being preferably formed of thin sheet metal, preferably aluminum, and have their upper edges rolled or curved around the pins or rods. The shutters 15 are curved or 10 bulged outwardly as clearly shown by the drawings, and they have their lower edges overlapping the upper edges of the adjacent shutters so that the shutters swing outwardly.

15 In using the device the ventilator is placed upon a chimney or other vent pipe. Normally when there is no air stirring outside of the ventilator and there is no draft within 20 the flue pipe then the shutters 15 are closed. However, when any air passes through the space formed between the flue pipe 11 and the sides 2 of the housing 1, then the shutters 15 will be automatically swung 25 outwardly. This same action will take place if there is a draft through the chimney. The outward curvature of the shutters is such that very little draft is required to open the same. Whenever the wind blows, 30 the shutters on the windward side will be forced by the wind into closed position while those on the leeward side will not be affected. Hence a perfect draft through the ventilator will be at all times maintained and there is 35 insurance against back drafts.

40 From the foregoing description taken in connection with the drawings, the construction, use, and operation of the device will be readily understood without a more extended explanation.

45 As various changes in form, proportion, and in the minor details of construction may be resorted to without departing from the spirit of this invention, it is to be understood that I do not wish to be limited to the construction herein shown and described other than as claimed.

I claim—

1. A ventilator of the class described com-

prising a housing closed at its top and open 50 at its bottom and provided with a window, and an outwardly swinging shutter hinged at its upper edge on a horizontal pivot in said window, said shutter being bulged outwardly to adapt it to be opened by the draft 55 passing into said housing through the open lower end of the same.

2. A ventilator of the class described comprising a housing closed at its top and open 60 at its bottom and provided with a plurality 65 of windows, and a series of outwardly swinging overlapping shutters hinged on horizontal pivots in each of said windows, said shutters being normally disposed in closed position and being bulged outwardly to cause 70 them to be opened by the draft passing into the housing.

3. A ventilator of the class described comprising a housing closed at its top and open 75 at its bottom and provided with a plurality 80 of radially disposed windows, the vertical side edges of said windows being bent inwardly to form window casings, forms secured to the interior side of said housing and having portions disposed parallel to and 85 spaced a slight distance from said window casings, and outwardly opening shutters having trunnions extending horizontally from the side edges near their upper ends, said trunnions projecting through said window 90 casings and having their ends abutting against said forms to prevent them from shifting longitudinally.

4. A ventilator of the class described comprising a hollow housing provided with 85 windows, strips of angle material having one 90 of their portions crimped around the upper and lower edges of said housing, a crown for said housing secured to the strip of angle material which is disposed at the top of the same, and shutters for said windows.

In testimony whereof I have hereunto set my hand in the presence of two subscribing witnesses.

ALBERT H. LUMM.
